LIGHT EMMITTING OPTICAL FIBRE DISPLAY

Dennis K. Bingaman, R.D. #1,
Dalmatia, Pa. 17017

Filed Sept. 7, 1972, Ser. No. 276,884

Term of patent 14 years

Int. Cl. 26—05

U.S. Cl. D48—20 C

FIG. 1

FIG. 3FIG. 4FIG. 1 is a perspective view of a light emitting fiber optic display showing my new design;

FIG. 2 is a bottom plan view thereof;

FIG. 3 is an end elevational view as seen from the left of FIG. 1, the fiber elements in the other rows being omitted for convenience of illustration;

FIG. 4 is a side elevational view thereof, the fiber elements in the other rows being omitted for convenience of illustration.

I claim:

The ornamental design for a light emitting optical fibre display, substantially as shown and described.
